US0D1060595S

(12) **United States Design Patent** (10) **Patent No.:** **US D1,060,595 S**
(45) **Date of Patent:** **** Feb. 4, 2025**

(54) **WASP LURE**

(71) Applicant: **Shenzhen Fengmang Network Technology Co., Ltd.**, Shenzhen (CN)

(72) Inventor: **Chaoran Liu**, Qingdao (CN)

(73) Assignee: **Shenzhen Fengmang Network Technology Co., Ltd.**, Shenzhen (CN)

(**) Term: **15 Years**

(21) Appl. No.: **29/967,904**

(22) Filed: **Oct. 14, 2024**

(51) LOC (15) Cl. **22-05**

(52) U.S. Cl.

USPC **D22/132**

(58) **Field of Classification Search**

USPC D22/128-130, 132; D21/650

CPC A01K 85/00; A01K 85/012; A01K 85/013;

A01K 85/019
